UNITED STATES PATENT OFFICE.

RUPERT H. TOMLINSON, OF ILION, NEW YORK.

CLOTHESLINE-SUPPORTING TROLLEY.

Application filed September 21, 1923. Serial No. 664,121.

To all whom it may concern:

Be it known that I, RUPERT H. TOMLINSON, a citizen of the United States, residing at Ilion, in the county of Herkimer and State of New York, have invented a new and useful Clothesline-Supporting Trolley, of which the following is a specification.

The present invention is a support for shiftable clothes lines or the like of the endless type, which will prevent the lower or clothes supporting strand or reach thereof from sagging, and will evenly distribute the weight suspended from the line on the upper or lower reaches thereof.

The main object of the invention is the production of a very simple and economical construction of support of this character which, when properly applied, will not become loose or fall from the line, and which insures perfect operation of the device at all times irrespective of weather conditions.

Other objects and features of the invention will appear as the specification proceeds and will be definitely pointed out in the appended claims.

In this specification and the annexed drawings, the invention is disclosed in the form in which it is considered to be the best, but the invention is not limited to such form because it is capable of being embodied in other forms; and it is to be understood that in and by the claims following the description herein it is intended to cover the invention in whatever form it may embody within the scope thereof.

In the drawings which show the preferred embodiment of the device as at present devised,

Figure 1 is a diagrammatical illustration of the invention as applied,

Fig. 2 is a face view of the support taken substantially on line 2—2 of Fig. 1, and

Fig. 3 is a side view of the support.

Referring particularly to the drawings, in which like characters denote similar and like parts in the several views thereof, and referred to in this specification, the support consists of a strand of wire A having a substantially straight portion 1, and has its end portions 2 and 3 bent upon itself and toward each other to form an elongated open loop, the body portion 1 forming one side wall of the loop, and the ends 2 and 3 the other side wall. The extremities of the end portions 2 and 3 overlap at a medial point in the length of the support, and are slightly

spaced apart, as clearly illustrated in Fig. 2, to form a restricted entrance X to receive the strands of the clothes line, the extremity a of the end portion 2 lying inside of the extremity b of the end portion 3. The wire strand A is of relatively flexible material so that the extremities a and b may be flexed under pressure as illustrated, to permit the entrance of the clothes lines. The portion 4 between the end portion 2 and the body portion 1, and forming the upper wall of the device, is substantially straight and forms an axis upon which is rotatably mounted a trolley wheel 5, having a suitable opening 6 therein to receive the portion 4.

The end portion 2 of the strand cooperates with the opposite and corresponding portion of the body 1 to provide what is termed a trolley passage B. The width between the end portion 2 and the corresponding portion of the wall 1 is slightly in excess of the diameter of the usual clothes line rope or cable, so as to provide a passage of restricted width to retain the cable and wheel in proper relation at all times, and to prevent jumping or slipping of the cable or wheel from engagement and binding between the wheel and the side walls of the support.

The end portion 3 is bent abruptly at its juncture with the side wall 1, and with the opposite corresponding portion of the side wall 1 forms a wedge shaped passage D in which the lower strand E of the clothes line is received, and tightly binds therein, the said corresponding portion of the side wall 1 and the end portion 3 diverging relative to each other from their juncture, at f, to form the V-shaped wedge slot D.

It will be further observed that the side wall 1 of the support is offset inwardly at its medial point at g, to bring the apex f of the wedge slot in direct vertical alignment with the radial axis of the trolley wheel 5, so that the weight taken up by the support will be evenly balanced on the wheel 5, and eliminate the tendency of the upper strand C of the line from slipping from engagement with the wheel 5, the wheel 5 being of course suitably grooved.

It will be further observed that the inner extremity a of the end portion 2 extends inwardly toward the side wall 1 to provide a restricted entrance of less diameter than the clothes line, thereby retaining at all

- times the upper strand of the line in the trolley passage *b*, and to prevent the lower or supporting strand or reach of the line from moving into the trolley passage. As before stated, however, the extremities *a* and *b* of the end sections can be deliberately flexed to permit the insertion or removal of the upper and lower reaches of the line in their respective passages, as may be desired.
- 10 After the support of this invention has been applied to the line, in the manner illustrated and described, a pull on either reach of the line *C* or *E* will cause the line to move over its supporting pulleys *H* and *I*, which may be suitably mounted in the manner commonly in practice, and the supports will be moved in the direction of the pull by reason of the lower strand of the line being tightly gripped in the wedge slot *D* and the trolley wheel 5 riding over the upper strand of the line. As many of these supports may be used as may be found desirable or necessary to eliminate sagging in the line, and to distribute the weight on the lower or supporting strand or reach of the line to the upper strand or reach.

When the line is not being used it is not necessary to remove the supports entirely from the line, but only necessary to remove the lower strand or reach from the wedge slot. Therefore it will be seen that as the clothes are being brought in the supports will collect at one end of the line, as illustrated in dotted line, Fig. 1, and can be brought again into use by simply inserting the lower strand or reach of the line into the wedge slot *D*, and properly spacing the supports relatively to each other.

The strand *E* of the line by its own weight and the weight which it supports, will bind itself to the wedge slot, as will be readily understood.

The above described clothes line support is a very simple and economical device which can be used with greater facility and convenience than present known devices.

Having thus described the invention,

what is claimed as new and desired to be secured by Letters Patent is:

1. A clothes line supporting trolley comprising a strand of wire having its end portions bent upon itself and toward each other, forming an elongated loop; the extremities of said end portions overlapping and being spaced apart, forming a restricted entrance to the loop; one end of said portions and the opposite portion of the loop, forming a line retaining passage, and the extremity of said end portion being extended into said loop to form an open restricted entrance to said passage; the other end portion of the strand cooperating with the opposite portion of the loop and providing a wedge slot therebetween in which the lower reach of the line is received and binds. 55

2. A clothes line supporting trolley comprising a strand of wire having its end portions bent toward each other to form an elongated loop, a trolley wheel journaled at the juncture of one of said end portions to the body of the strand by having said strand extending through a central opening therein, the other end portion converging toward its juncture with the body of the strand to form a wedge slot at the other end of the loop, the extremities of said end portions overlapping and being spaced apart forming a restricted entrance to within the loop. 75

3. A clothesline supporting trolley as set forth in claim 2 further characterized by the extremity of the end portion adjacent the trolley wheel, being extended inwardly and toward the body of the strand, to form a restricted entrance opening dividing the wedge slot from the trolley wheel end of the loop, whereby the portions of the line engaging the trolley wheel and in said slot are retained in their respective positions in the loop. 85

In testimony whereof I have hereunto set my hand.

RUPERT H. TOMLINSON.
